[57] CLAIM

The ornamental design for a loudspeaker with removable grille cloth, as shown and described.

DESCRIPTION

FIG. 1 is a top, front and right-side perspective view of a loudspeaker with removable grille cloth showing our new design;

FIG. 2 is an enlarged front elevational view thereof, the rear thereof being void of ornamentation;

FIG. 3 is a front elevational view thereof, with the removable grille cloth removed;

FIG. 4 is a right-side elevational view thereof;

FIG. 5 is a left-side elevational view thereof; and,

FIG. 6 is a top plan view thereof, the bottom thereof being void of ornamentation.
